UNITED STATES PATENT OFFICE.

WINFIELD S. BANNER, OF UNIONVILLE, MISSOURI.

SALE OR ACCOUNT BOOK.

SPECIFICATION forming part of Letters Patent No. 664,828, dated January 1, 1901.

Application filed March 24, 1900. Serial No. 10,034. (No model.)

To all whom it may concern:

Be it known that I, WINFIELD S. BANNER, a citizen of the United States, residing at Unionville, in the county of Putnam and State of Missouri, have invented a new and useful 5 Sale or Account Book, of which the following is a specification.

My invention relates to account-books, and has for its object to produce a book of this 10 class by means of which the leaves may be increased or decreased at will and the accounts secured to the different leaves, whereby any account in the book may be readily found and the necessity for posting the accounts 15 from one book to another is avoided.

With this object in view my invention consists in the improved construction and novel arrangement of parts of a book, as will be hereinafter more fully set forth.

20 In the accompanying drawings, in which the same reference-numerals indicate corresponding parts in each of the views in which they occur, Figure 1 is a perspective view of a book closed made in accordance with my 25 invention. Fig. 2 is a plan view of the same open. Fig. 3 is a transverse sectional view of Fig. 1. Fig. 4 is a longitudinal sectional view of the book. Fig. 5 is a detail view of one of the leaves of my improved book; and 30 Fig. 6 is an enlarged sectional detail view of a portion of the back, the leaves being omitted to avoid confusion.

Referring more particularly to the drawings, 1 indicates one of the book-covers of 35 my improved book, and 2 indicates the other one. The rear cover 1 has a binding-flap 3 permanently secured to it at one edge, and the opposite edge of the flap is arranged to fold over the rear edge of the front cover and 40 be movably connected therewith by means of elastic strips or connectors 4, which when secured to the interior pass through suitable perforations 5 in the cover and are secured near the forward edges of the cover upon the 45 inside. The inner face of the binding-flap 3 is provided with a pocket-like lining 6, which is secured thereto at its edges and is provided at suitable distances apart with transverse slits or openings 7. Each of the leaves 8 of 50 the book and also the front cover 2 is provided with a series of loops 9, projecting from their rear edges in position to pass through

the slits or openings in the lining 6. Suitable attaching devices—as, for instance, cords or wires 10—are passed longitudinally through 55 the loops to the rear of the lining after the leaves have been placed in position, thereby preventing the removal of the leaves except upon the withdrawal of the fasteners 10. The same style of fastener may be utilized for connecting the strips or connectors 4 with the lining, as all that will be necessary is to provide either end of each of the connectors with a suitable loop 15, which may be passed through the opening in the lining and secured therein 65 by inserting a wire through the loops of all the connectors in the same manner that is done for each of the leaves. For the purpose of the insertion and removal of these fasteners one end of the lining, preferably the upper end, may be temporarily closed or permanently left open.

If desired, a suitable extensible hasp or clamp 11 is secured to one of the covers in position to have its opposite end engage with 75 the other cover and hold the book closed.

For convenient access to the accounts within the book I prefer to form the leaves of the index narrower than the account-leaves, so that the letters of the alphabet 12 may be exposed upon the outer edges of the index portion in the usual manner, and the numbering of the pages of the leaves 13 will project beyond the edges of the index in position to be seen at all times. Although the accounts may 85 be arranged upon the different leaves in any suitable manner, temporarily or permanently, I prefer to provide each of the leaves with suitable retaining mechanism—as, for instance, flexible elastic bands 14—upon one or 90 both sides of the leaves, under which the accounts of the different persons may be temporarily secured.

As above described, it is evident that a great many accounts can be conveniently kept 95 or stored in my book in such a manner that access can be had to any particular account with quickness and despatch. For instance, when it is desired to find any particular account the index is opened at the page on 100 which his name has been properly indexed in any suitable manner and in which the number of the page and, if desired, the column on that page on which the account will be

found. As the numbering of the pages is exposed beyond the edges of the leaves of the index, the book can be immediately opened to the desired page and the account located 5 almost instantly. By keeping the accounts in this manner the entries for each account may be made upon the account itself, and thereby the necessity of transferring the accounts to a separate book is avoided, thereby 10 simplifying the necessary bookkeeping to the greatest extent. If at any time any account is closed and it is not desired to further retain it in the book, it can be removed from its fastening and another account put in its 15 place, the index being suitably changed to correspond with the change in the accounts. With the increase or decrease of the number of accounts to be kept in the book the number of account-leaves can be varied to suit 20 conditions by simply withdrawing the wires of any of the leaves that are to be removed or by inserting new leaves and introducing other wires behind the lining when the inside of the book is to be increased. As the binding 25 of the book is made flexible and the strips by means of which it is connected with the front cover are of sufficient strength to always keep the binding drawn taut and smooth, the book will always present a neat and tidy 30 appearance.

Instead of utilizing my improved book for accounts, as heretofore described, it can be used for a sales-book or other similar purposes. The leaves can be arranged so as to 35 be temporarily secured between the covers, and accounts or any other desired matter may be placed upon them, or instead of leaves suitable envelops or small-sized packages may be provided with the loops 9 and be secured to the lining in the same manner as the 40 leaves, thereby producing a very convenient scrap-book.

It is evident that other changes and modifications may be made without departing from

the spirit of my invention, and I reserve the 45 right to make all such changes and variations in the form and construction of my improved book as will come within the scope of my invention.

Having thus fully described my invention, 50 what I claim as new, and desire to secure by Letters Patent, is—

1. In an account-book, the combination, with two covers, one of which is provided with a binding-flap permanently secured thereto 55 at one edge and the other one is provided with means for yieldingly securing said flap thereto, of a lining secured to said flap provided with transverse openings, a series of leaves between the covers, each of which is provided 60 with loops to pass through the openings in the lining, and a fastener through said loops to the rear of said lining, substantially as described.

2. In an account-book, the combination, 65 with two covers, one of which is provided with a series of openings, of a binding-flap secured to the imperforate cover at one edge, a lining secured to the flap and provided with transverse openings, a series of leaves between the 70 covers, each of said leaves and the perforated cover being provided with a series of loops upon its rear edge in position to pass through the openings in the lining, a fastener through each series of loops to the rear of the lining, 75 yielding strips secured to the inside of the perforated cover near its front edge, the free end of each of which is provided with a loop and is passed through one of the openings in the cover into the corresponding opening in 80 the lining, a fastener through said loops, and an extensible hasp at the free edges of said covers.

WINFIELD S. BANNER.
